UNITED STATES PATENT OFFICE.

HARRY H. PRESCOTT AND EDWARD H. CONSIDINE, OF CHICAGO, ILLINOIS.

DOUBLE CHECK-VALVE.

1,240,254.

Specification of Letters Patent. Patented Sept. 18, 1917.

Application filed October 24, 1916. Serial No. 127,439.

To all whom it may concern:

Be it known that we, HARRY H. PRESCOTT and EDWARD H. CONSIDINE, citizens of the United States, residing at Chicago, in 5 the county of Cook, State of Illinois, have invented a new and useful Double Check-Valve, of which the following is a specification.

The present invention appertains generally to valves, and aims to provide an automatic double check valve for a vent pipe or the like, the structure being attachable to one end of a pipe for admitting air, gas or fluid into the pipe from one port and 15 discharging the air or fluid through another port, the end of the pipe being normally closed by the valves when there is no flow of fluid.

It is the object of the invention to provide a double check valve of novel and improved construction, which is extremely simple and inexpensive, as well as being thoroughly practical and efficient in use.

With the foregoing and other objects in 25 view which will appear as the description proceeds, the invention resides in the combination and arrangement of parts and in the details of construction hereinafter described and claimed, it being understood that 30 changes in the precise embodiment of the invention herein disclosed can be made within the scope of what is claimed, without departing from the spirit of the invention.

The invention is illustrated in the accompanying drawing, wherein:—

Figure 1 is a perspective view of the device.

Fig. 2 is a median vertical section thereof.

In carrying out the present invention, 40 there is provided a horizontally elongated relatively flat casing 1 of rectangular outline in side elevation, with its bottom open. The casing 1 is provided within its lower portion intermediate the ends with a short 45 conduit 2 terminating in a depending nipple 3 which is threaded or otherwise formed for attachment to the upper end of a vent pipe, or the like. The conduit or portion 2 provides opposite downwardly opening ports 4 and 5 between the conduit 2 and the ends of the casing, the port 4 being the exhaust or discharge port, and the port 5 being the inlet port.

The casing is provided between its sides 55 with a vertical partition 6 extending from the top of the casing to the upper end of

the conduit 2 between opposite sides thereof, and said partition has an extension 7 projecting downwardly within the conduit 2, there being a port or opening 8 between 60 the partition 6 and one side of the conduit 2, and a horizontal partition 9 between the partition 6 and the opposite side of the conduit. The partition 9 is provided with an opening 10 and an upstanding annular boss 65 11 surrounding said opening and providing a seat for a ball valve 12 which seats by gravity upon the valve seat, and this provides a check valve for permitting the flow of air or fluid from the pipe to the outlet or discharge port 4 but to prevent the flow of air or fluid into the pipe from said outlet or port 4. The casing 1 has a transverse bar or partition 13 between its sides above that side wall of the conduit 2 with 70 75 which the partition 9 is integral, and said bar 13 is spaced from the partition 9 and top of the casing, to provide openings above and below the same. These openings above and below the bar 13 permit of the flow of 80 fluid past said bar without interference, and the lower opening permits sediment and other foreign matter to be drained or cleaned from the valve seat. The bar 13 85 confines the valve 12 for movement above the valve seat, and prevents the valve from rolling off of the valve seat 11 and partition 9 into the opening or outlet 4.

A horizontal partition 14, preferably in the same plane as the partition 9, connects 90 that side wall of the conduit 2 remote from the partition 9 with the respective ends of the casing and is provided with an opening 15 and an upstanding boss 16 surrounding said opening and providing a valve seat for a 95 ball valve 17. Said valve 17 is seatable by gravity, the same as the valve 12, and permits of the flow of air or fluid into the casing by way of the inlet 5, to prevent the discharge of fluid through said inlet. The 100 casing has a second transverse bar or partition 18 disposed in a vertical plane, the same as the bar 13, and connecting the sides of the casing, said bar being spaced from the conduit 2 and top of the casing, to provide 105 openings above and below the same for the flow of fluid, the lower opening below the bar 18 permitting the sediment or other foreign matter to be drained or cleaned from the valve seat 16.

The parts 2, 3, 6, 7, 9, 13, 14 and 18 can 110 all be cast integral with the casing 1,

thereby to provide a cheap yet efficient construction.

The top of the casing 1 is provided with openings 19 and 20 above the respective 5 valve seats 11 and 16, and said openings are normally closed by the removable screw plugs 21 and 22, respectively. When the plugs are removed, this gives access to the valves and their seats, whereby the valves can be re-10 moved and replaced, and the valve seats are cleaned.

Air or other fluid can flow into the pipe to which the nipple 3 is attached, by way of the inlet 5, opening 15, opening or port 15 8, conduit 2 and nipple 3, the valve 12 remaining seated, but when the air or fluid is forced from the pipe, the valve 17 will seat and the valve 12 is unseated to permit the air or fluid to be discharged by way of the 20 opening 10 and outlet 4. The structure can be used upon the upper end of a vent pipe, or for various other purposes for which it is suitable.

Having thus described the invention, what 25 is claimed is:—

1. A valve structure embodying a valve casing having a lower portion for attachment to the upper end of a pipe, lower inlet and outlet ports at opposite sides of 30 said portion, a vertical partition above said portion, a horizontal partition between the aforesaid partition and one side of said portion having an opening and a valve seat, and a horizontal partition between the opposite

side of said portion and the wall of the casing above the inlet port and having an opening and a valve seat, and valves seatable upon said seats. 35

2. A valve structure embodying a horizontally elongated valve casing having a lower portion intermediate its ends for attachment to the upper end of a pipe and having outlet and inlet ports between said portion and the ends of the casing opening downwardly, said casing having a vertical 40 partition extending from its top to a point between opposite sides of said portion and a horizontal partition between the aforesaid partition and that side of said portion adjacent to the outlet port, the casing having another horizontal partition between the opposite side of said portion and the respective end wall of the casing above the inlet port, the horizontal partitions each having an opening and a valve seat, ball valves seatable 45 on said seats, the casing having bars between its sides for retaining the valves above the seats, the top of the casing having openings above the valve seats, and removable closures for said openings. 50

In testimony that we claim the foregoing as our own, we have hereto affixed our signatures in the presence of two witnesses.

HARRY H. PRESCOTT.
EDWARD H. CONSIDINE.
